Primary Examiner — Wan Laymon*Assistant Examiner* — Clint A Samuel(74) *Attorney, Agent, or Firm* — Maschoff Brennan(57) **CLAIM**

The ornamental design for a ball roller assembly, as shown and described.

DESCRIPTION

FIG. 1 is an upper perspective view of a ball roller assembly showing the present disclosure.

FIG. 2 is a lower perspective view of the ball roller assembly;

FIG. 3 is a front view of the ball roller assembly;

FIG. 4 is a rear view of the ball roller assembly;

FIG. 5 is a right side view of the ball roller assembly;

FIG. 6 is a left side view of the ball roller assembly;

FIG. 7 is a top view of the ball roller assembly; and,

FIG. 8 is a bottom view of the ball roller assembly.

The broken lines showing in the drawings are for the purpose of illustrating environmental structure and form no part of the claimed design.

1 Claim, 8 Drawing Sheets(56)
